[57] CLAIM

The ornamental design for a spark plug inserter-/remover, as shown and described.

DESCRIPTION

FIG. 1 is a side perspective view of a spark plug inserter/remover showing my new design.

FIG. 2 is a side elevational view thereof, all other side elevations being identical;

FIG. 3 is a left end elevational view thereof;

FIG. 4 is a right end elevational view thereof;

FIG. 5 is a cross-sectional view thereof, taken along the line 5—5 in FIG. 2;

The broken line showing of the spark plug and engine block in FIG. 1 is for illustrative purposes only and forms no part of the claimed design.
